THOMAS W. ROBISON, OF HILLSDALE, OREGON

QUICK DROP ATTACHMENT FOR TYPE CASTING MACHINES

Application filed March 24, 1931. Serial No. 524,839.

This invention relates generally to the art of printing, and particularly to type casting machines.

The main object of this invention is the provision of a quick drop attachment for intertype casting machines which will be more readily operable than the quick drop attachments now in use.

The second object is the provision of an attachment which can be installed on existing machines without interfering with their operation in any way and without altering or drilling numerous holes therein and with the addition of only a minimum number of new parts.

These, and other objects, will become more apparent from the specification following as illustrated in the accompanying drawings, in which:

20 Fig. 1 is a perspective view showing the related parts of an intertype machine and the new attachment thereto.

Fig. 2 is a vertical section along the line 2—2 in Fig. 1.

25 Fig. 3 is a horizontal section along the lines 3—3 in Fig. 2.

Fig. 4 is a fragmentary view showing the latched position of the quick drop block.

30 Fig. 5 is similar to Fig. 4 showing the unlatched position of the quick drop block.

Fig. 6 is a similar view showing the pot pump cam roll riding upon the block.

Fig. 7 is a similar view showing the quick drop block pushed back to a latched position.

35 Similar numbers of reference refer to similar parts throughout the several views.

Before entering into a description of this device it will be understood that what is known as the quick drop attachment on type

40 casting machines is applied to the pot pump cam in front of the dip which permits the pump lever to make its casting stroke. It is used when casting fine hair line borders and if difficulties are encountered in securing a

45 good face on the slugs, as well as in casting type having a large face and a relatively small body. The function of the device is to permit the plunger to descend more rapidly than is required for ordinary work for the

50 purpose of injecting the metal into the mold

with greater force, sufficient, in fact, to project same instantaneously over the entire face of the matrices.

In order to illustrate this invention there is shown a number of related elements of an 55 intertype casting machine, among which is a mold gear arm 10 which is adjacent to the casting pot 11, through the top of which extends a plunger 12 by whose downward descent metal is forced from the pot 11 60 through the channel 13 into the matrices (not shown). To the plunger 12 is attached a pot pump lever 14 which is urged downwardly by the pot pump spring 15 acting through the rod 16 which passes through the 65 bracket 17.

Passing through the bracket 17 is a pot 70 pump lever shaft 18 identical with the one now in use, except that it is made tubular and forms a bearing for a rock shaft 19, on one end of which is mounted a latch operating lever 20, and on the other end of which is mounted a rock lever 21 which is joined by means of a pin 22 to a bent rod 23 which guides at its opposite end 24 in the frame 75 casting 25 and has on its extreme end a button 26 by means of which it may be moved in or out. The pin 22 is connected to the pin 27 by means of a spring 28 adapted to urge the lever 21 toward one of its extreme positions.

On the lower end 29 of the pump lever 14 is mounted a pot pump cam roll 30 which rides on the surface of the pot pump cam 31. At the dip of the pump cam 31 is hingedly 85 mounted a quick drop block 32 which forms a part of the high portion 33 of the cam 31. A spring 34 is interposed between the block 32 and the cam 31 normally urging same apart against the stop 35, providing a yielding dip for the cam 31. However, when the quick drop action is not desired the block 32 is latched to a retracted position (as shown in Figures 1 and 4) by means of a block latch 36 which engages the square lug 37 on the 90 side of the block 32. The block latch 36 is provided with a spring arm 38 whose end is urged toward the pin 39, upon which the block 32 is hinged by means of the spring 40.

On the block latch 36 is also formed a 100

roller arm 41 whose roller 42 lies in the path of a latch tripping arm 43 which is hinged on the end 29 of the pot pump lever 14 by means of a screw 44. The arm 43 is connected to the lever 20 by means of a link 45.

- The operation of the device is as follows: If it is desired to use the quick drop attachment the operator who is conveniently near the button 26 merely pulls it out causing it to take the position shown in Fig. 1. As the cam 31 rotates the roller 42 comes into contact with the arm 43 causing the latch 36 to be disengaged from the lug 37, permitting the block 32 to move outwardly—that is, to 15 a quick drop position—(as shown in Fig. 5). As the roll 30 moves over the face 46 of the block 32 it permits a quick descent of the roll 30, and at the same time re-latches the block 32 in the position shown in Fig. 7.
- 20 It is desirable to provide a spring 47 between the arm 43 and the lever end 29 for the purpose of preventing injury to the parts should the cam 31 be reversed, in which case the roller 42 might strike solidly against the 25 projecting end of the arm 43.

It is desirable to provide a clearance between the edge 48 of the latch 36 and the lug 37 in order that the latch 36 may firmly engage the lug 37.

- 30 If it is desired to dispense with the quick drop action the operator merely pushes the button 26 inwardly, which causes the arm 43 to be lifted out of the path of the roller 42 permitting the latch 36 to hold the block 32 35 in the position shown in Fig. 4 throughout the revolution of the cam.

It will be observed that in the construction of this attachment care has been taken not to interfere with the operation of the machine 40 in any way, nor to require the alteration of its parts other than those mentioned, but making it possible for the operator to easily and quickly avail himself of the advantages of the quick drop action without rising from 45 his seat.

I claim:

- 50 1. A quick drop attachment for type casting machines having in combination a quick drop block hingedly mounted in front of the dip of the pump cam and having spring means for urging the outer portion thereof away from the high portion of said pump cam, a latch for holding said block in a retracted position, a latch tripping arm adapted to be swung across the path of said latch for the purpose of unlatching same by the rotation of said cam, and means for moving said arm into and out of a latch engaging position.
- 55 60 2. A quick drop mechanism for type casting machines comprising the combination of a pump cam having a yieldable dip with means for latching said dip into a retracted position, and means for releasing said latch by the rotation of said cam.

3. A quick drop mechanism for type casting machines comprising the combination of a pump cam having a yieldable dip with means for latching said dip into a retracted position, means for releasing said latch by the rotation of said cam, together with means for moving said latch release to an operative or an inoperative position.

4. A quick drop operating mechanism for type casting machines consisting of a rock shaft mounted in the pot pump lever shaft of a casting machine, a rock lever mounted on one end of said rock shaft, a latch operating lever at the other end of said rock shaft, a rod connected to said rock lever for the purpose of operating same, a latch tripping arm hinged in the path of said quick drop mechanism having means for operating same from the latch operating lever, and a latch adapted to normally hold said quick drop mechanism inoperative having a roller arm thereon adapted to engage said latch tripping arm when moved into the path thereof by said rod.

5. A quick drop mechanism for type casting machines having in combination a pot pump cam provided with a dip over which the cam roller drops during the casting operation, a yieldable block hinged in front of said dip forming an extension for the raised portion of the cam, a latch on said cam normally holding said block in a retracted position, and a trip for said latch operable from the operator's side of the casting machine.
